UNITED STATES PATENT OFFICE

2,614,695

ROTARY SCREEN COMMINUTING DEVICE

Carl H. Nordell, Palm Springs, Calif.

Application November 9, 1948, Serial No. 59,089

9 Claims. (Cl. 210—152)

1

This invention relates to a comminuting device adapted to comminute solids in a liquid stream, particularly in a stream of sewage flowing into a sewage treatment plant, so that the comminuted solids may be carried through a screen along with the liquid sewage.

In accordance with the present invention, a drum type screen is positioned between the influent and effluent channels so that sewage must pass through the screen before it can flow into the apparatus in which it is to be treated. The drum screen rotates at a relatively slow speed and is engaged by a cutting cylinder rotating at a relatively high speed. The cutting cylinder acts as a transfer unit to sweep the solids from the surface of the screen and move them to a stationary comb. The solids are then comminuted between the teeth of the cutting cylinder and the teeth of the comb, and then flow along with the liquid sewage through the screen into the effluent channel and then to the sewage treatment apparatus. The comminution of the solids takes place in the stream and upstream and off of the face of the screen.

The cutting cylinder and comb are mounted in fixed relationship to each other and are pivoted as a unit so that they may be swung up out of the sewage for inspection and repair. An adjustable stop member insures the proper positioning of the cutting cylinder relative to the screen when it is swung into operative position adjacent the screen. The cutting cylinder comprises a plurality of cutting disks and spacers mounted on a rotating shaft. The disks are so keyed to the shaft that the cutting teeth of the disks are staggered.

The structure by which the above noted advantages are attained will be described in the following specification, taken in conjunction with the accompanying drawings, in which:

Figure 1 is a plan view of an influent channel with the rotating drum screen and comminuting device positioned therein, with the comminuting device shown in its raised position in dotted lines;

Fig. 2 is a front elevation of the screen and comminuting device showing the mechanism for pivotally raising the comminuting device out of the sewage for inspection and repairs;

Fig. 3 is a cross sectional view, taken along the line 3—3 of Fig. 2, showing the interior structure of the screen and the mechanism for driving the cutting cylinder and the screen;

Fig. 4 is a cross sectional view, taken along the line 4—4 of Fig. 3;

Fig. 5 is a cross sectional view, taken along the

2

line 5—5, showing the radial structure of the interior of the rotating screen;

Fig. 6 is a cross sectional view through the influent and effluent channels showing the screen and comminuting device, and showing, in dotted lines, the comminuting device swung up into position for inspection and repair;

Fig. 7 is a detail plan view of one of the cutting disks;

Fig. 8 is a fragmentary perspective view of the cutting comb; and

Fig. 9 is a fragmentary cross sectional view showing the cutting cylinder and comb in operative position.

In the drawings, the reference numeral 2 designates the influent channel, through which the unscreened sewage flows, and the numeral 3 designates the effluent channel, through which the screened sewage flows. Both channels are made of any suitable construction, but are preferably of concrete. Channel 3 is below the bottom of channel 2 and is connected thereto by means of an opening 4 in the bottom of channel 2. Opening 4 is protected by a screen 5, hereinafter described, so that no unscreened sewage can pass through opening 4.

Screen 5 comprises a central hub 6, a plurality of vertical webs 7 extending radially from said hub, and a plurality of vertically spaced screen bars 8 encircling the outer ends of said webs. Each screen bar 8 (Figs. 3, 5 and 9) comprises a channel shaped member having its base 9 secured to the outer vertical edges of webs 7 in any suitable manner, as by welding. Side walls 10 and 11 of each screen bar 8 are spaced uniformly from side walls of adjacent screen bars. The liquid sewage and comminuted solids pass from influent channel 2 through the spaces between adjacent screen bars 8, through opening 4, and into effluent channel 3. A channel iron 12 is secured at the outer bottom edges of webs 7 to reinforce the bottom edge of screen 5. Channel 12 is reversed, relative to channels 8, and its back wall 13 forms a smooth band at the bottom of the screen.

Opening 4 is surrounded by an upstanding circular wall 14 secured to the floor of channel 2 in any suitable manner, as by bolts 15. Wall 14 is in the form of an inverted channel shaped member having a flat top wall 16 which forms a base to which the bottom of a circular flexible seal 17 is secured, as indicated at 18. Seal 17 may be of any suitable material, but is preferably of rubber, particularly an oil-insoluble rubber such as neoprene or similar synthetic rub-

ber. The other edge of seal 17 engages back wall 13 of channel 12, as shown in Fig. 3. Seal 17 forms a close enough fit between members 12 and 14 so that no solids in the sewage can enter opening 4 through the space between the bottom of screen 5 and the floor of channel 2, thereby insuring that the solids will be screened and comminuted and then flowed with the sewage through the screen.

The top of screen 5 is covered by a flat annular plate 20 secured to the top edges of webs 7 in any suitable manner. The top wall 21 of hub 6 has a peripheral flange 22 which supports the inner edge of plate 20. The inner edge of plate 20 may be screwed to flange 22, as indicated at 23, Fig. 3, or it may be secured by any other suitable means. Plate 20 prevents any unscreened sewage from getting inside screen 5 through the top. Even if the level of sewage rises above the top of screen 5, plate 20 is ample protection against the entrance of unscreened sewage to the inside of the screen, except through the spaces between the screen bars.

Hub 6, and therefore screen 5, is secured to a flange 24 extending circumferentially from the bottom of a shaft 25, by means of bolts 26. In order to center hub 6 accurately with respect to shaft 25, a recess 27 is provided in the top surface of top wall 21 and a complementary projection 28 is provided on the bottom surface of shaft 25. Any suitable centering means may be used, however.

Shaft 25 is rotated at a slow rate of speed by a motor 29, through gearing now to be described, and screen 5 is rotated therewith.

As shown best in Figs. 3 and 4, motor 29 rotates a shaft 30 through a coupling 31. A worm gear 32 is mounted on shaft 30 and rotates a worm wheel 33. Worm wheel 33 rotates another worm gear 34 through a shaft 35 and flexible couplings 36 and 37. A worm wheel 38, mounted on a shaft 39, is rotated by worm gear 34. Shaft 39 is connected to shaft 25 through a coupling 40.

A housing 41 encloses all the gearing described above from shaft 39 to coupling 40. Housing 41 is bolted to the top surface of walls 42 and 43, forming channel 2, as indicated at 44, Fig. 1. A plate 45 bolted to housing 41 over an opening 46 in the top of housing 41, provides access to the gearing.

Shaft 30 extends through an opening 47 in the top of housing 41 and a tubular member 48 bolted to housing 41, as indicated at 49, provides an enclosure for the upper portion of shaft 30 and coupling 31. The base of motor 29 is bolted to tubular member 48, as shown at 50. Worm gear 32 and worm wheel 33 are provided with an individual housing 51. Bearings 52 and 53, on shaft 30 above and below worm gear 32, are held in housing 51 by end plates 54 and 55 secured thereto by bolts 56.

Worm gear 34 and worm wheel 38 also are provided with an individual housing 57. A bearing 58, extending around shaft 39 above worm wheel 38 is held in place by a top plate 59 secured to housing 57 by means of bolts 60. A bearing 61, at the bottom of worm wheel 38 is held in place by the top of a cap member 62. A circumferential flange 63 at the bottom of cap member 62 is bolted to a housing 64, as indicated at 65. Coupling 40 extends through an opening 66 in the bottom of housing 41, and housing 64 is secured to the bottom of housing 41 around opening 66 by means of bolts 67.

Housing 64 encloses the bottom portion of 75

coupling 40 and also supports a bearing 68 encircling shaft 25 below coupling 40 and another bearing 69 at the bottom of shaft 25. An oil seal 70 is held against bearing 69 by an annular disk 71 secured to the bottom of housing 64 by means of bolts 72.

Shaft 30 extends through an opening 73 in the bottom of housing 41 and rotates a shaft 74 through a split coupling 75. There is no reduction gearing between shafts 30 and 74, and, therefore, shaft 74 is rotated at a high rate of speed, compared to the rotation of shaft 25 which controls the rotary motion of drum screen 5. The portion of shaft 74 just below coupling 75 is enclosed in a housing 76. Bearings 77 and 78 are mounted in housing 76 adjacent its top and bottom. End caps 79 and 80 hold bearings 77 and 78 in place.

A plurality of cutting disks 81 (Figs. 7 and 9) are mounted in spaced relationship on the lower end of shaft 74 to form a cutting cylinder 82. The uppermost and lowermost disks 81 may be held in place on shaft 74 in any suitable manner and the intermediate disks are held in spaced relationship on the shaft by means of spacers 83. Each disk 81 comprises an annular member having a plurality of laterally projecting teeth 83 extending from its outer edge. The inner edge of each disk is notched, as indicated at 84 and 85. Notches 84 and 85 are uniform in size, but are each offset slightly different distances from diametrically opposite teeth 83. Each disk 81 is exactly alike so that only one stock of parts is required to replace any disk in the cutting cylinder whenever the teeth of any disk become worn.

The portion of shaft 74 on which disks 81 are mounted is provided with a spline or key 86 of a size to fit snugly into either notch 84 or 85. Spline 86 is preferably driven into a longitudinal recess or keyway 87 in shaft 74, but may be secured in any other suitable manner. Spacers 83 are interposed between disks 81 as they are positioned on shaft 74. The provision of a pair of notches 84 and 85 in each disk 81, only one of which notches is aligned with spline 86, makes it possible to obtain a vertically staggered arrangement of teeth 83 on the periphery of cutting cylinder 82 by alternately engaging notches 84 and 85 and reversing half the disks as they are mounted on shaft 74. The spacing of teeth 83 on the periphery of disks 81 is sufficiently close so that the four different positions relative to spline 86 provides a fine staggering of teeth over the entire peripheral area of cutting cylinder 82.

Cutting cylinder 82 is rotated at a relatively high rate of speed, about 250 to 750 R. P. M., and drum screen 5 is rotated at a relatively low rate of speed, about 2 to 20 R. P. M. As cutting cylinder 82 is rotated, teeth 83 pass between side walls 10 and 11 of screen bars 8 on drum screen 5 and remove solids from the screen and sweep these solids around to a cutting comb 89 vertically mounted on the lower portion of a supporting member 90.

The peripheral surfaces of spacers 83 may be roughened in any suitable manner, as indicated at 88', to help sweep solids, particularly rags, away from screen 5. These roughened surfaces rotating very close to the screen bars pull the rags and other fibrous material away from the screen and wrap it around its own periphery. When the thickness of this fibrous material builds up sufficiently, it is engaged by the cutting teeth 94 on comb 89 and by screen bars 8 and webs 7.

and shredded into very fine fibers which pass through the screen with the liquid sewage. Some solids, floating in the stream of unscreened sewage may not impinge on screen 5, but may be carried by the flow of sewage directly to comb 89.

Screen 5 may be positioned anywhere in channel 2 but is preferably positioned eccentrically of the end of channel 2 so that the major portion of the flow travels with the rotation. The minor portion of the flow is directed against the cutting cylinder so as to prevent any tendency of the solids to pack together and thus make possible the free movement of the comminuted material through the screen.

The forwardly projecting edge of comb 89 is provided with a plurality of recesses 91 vertically aligned with disks 81 so that teeth 83 pass therebetween. The areas on comb 89 intermediate the recesses are serrated to provide teeth 94. Solids carried to the proper side of comb 89 either by the rotation of cutting cylinder 82 or by the flow of liquid sewage are caught between teeth 83 and recesses 91 and between teeth 94 and the periphery of spacers 88 and are thoroughly comminuted so that they will flow with the rest of the sewage through screen 5.

Member 90, which carries comb 89, is bifurcated at its upper end and its upper arms 95 and 96 are pivoted to housing 41 by means of studs 97 and 98, as shown in Figs. 2 and 4. Studs 97 and 98 are secured to arms 95 and 96 by means of pins 99 and 100. Washers 101 and 102 are positioned between arms 95 and 96 and housing 41 to space the arms from the housing.

The lower portion of member 90 is preferably hollow, as indicated at 103 (Figs. 3 and 5), to reduce its weight. Housing 76 is integral with member 90 so that shaft 74 and cutting cylinder 82 may be moved pivotally as a unit with member 90. A worm gear 104 engages a worm wheel section 105 to move member 90 about pivot 97-98. Worm wheel 105 is rigidly secured to arm 95. Worm gear 104 is rotatably mounted in a bracket 106 secured to the bottom of housing 41. Worm gear 104 is shown as being actuated by a hand operated crank 107, through shaft 104', but it is obvious that a motor may be substituted for crank 107.

Coupling 75 is split so as to separate at its joint when member 90, cutting cylinder 82 and comb 89 are raised for inspection or repair, as shown in dotted lines in Fig. 6. A bracket 108 projecting from the bottom of member 90 is provided with an adjustable screw 109. An abutment 110 projecting laterally from circular wall 14 is engaged by screw 109 when cutting cylinder 82 is in the comminuting position to regulate the position of cutting cylinder 82 relative to screen 5.

Although I have described a preferred embodiment of my invention in considerable detail, it will be understood that the description is intended to be illustrative, rather than restrictive, as many details may be modified or changed, without departing from the spirit or scope of the invention. Accordingly, I do not desire to be restricted to the exact details of the structure described.

I claim:

1. In combination with an influent channel and an effluent channel for a moving liquid stream carrying solids to be comminuted, a rotatably mounted drum screen positioned between said channels to prevent unscreened liquid from passing from said influent channel to said ef-

fluent channel, a rotatably mounted cutting cylinder positioned in said influent channel adjacent the periphery of said rotatably mounted screen, a plurality of teeth projecting laterally from the periphery of said cylinder into cooperative relationship with said screen, and a comb positioned adjacent the periphery of said cutting cylinder and cooperating with said teeth to comminute solids in said unscreened liquid, said cutting cylinder and said comb being upstream of said screen with the cutting cylinder intermediate said screen and said comb, the teeth of said cutting cylinder serving upon rotation of said cylinder to remove solids from said screen and carry them to the said comb for comminution in the stream and upstream and off of the face of the screen:

2. In combination with a comminuting device comprising a rotatably mounted cutting cylinder having a plurality of teeth projecting laterally therefrom and a comb positioned in juxtaposition to said cylinder and cooperating with said teeth to comminute solids, a rotatably mounted drum screen in cooperative relationship with the teeth of said cutting cylinder along a longitudinal line diametrically opposite the line of cooperative relationship between the teeth of said cylinder and said comb.

3. In combination with a rotatably mounted drum screen comprising a plurality of vertically spaced channel shaped screen bars having outwardly projecting side walls, a rotatably mounted cutting cylinder having a plurality of laterally projecting teeth passing between the side walls of said screen bars during the rotation of said screen and cutting cylinder, and a comb spaced from said screen cooperating with said cylinder to comminute solids which are carried by said cylinder from said screen to said comb, said cutting cylinder being intermediate said screen and said comb.

4. In an apparatus for treating sewage which includes a screen placed in a channel or conduit through which sewage flows, said screen intercepting lumps of solid matter and preventing said lumps from flowing through said screen, a transfer and comminuting unit disposed adjacent the upstream surface of the screen, said unit comprising a cutting cylinder, a plurality of teeth projecting laterally therefrom, and a comb positioned adjacent said cutting cylinder in an area spaced from said screen, and means for causing relative rotary movement between said screen and said unit whereby substantially the whole outer surface of said screen is periodically swept by said unit, said cutting cylinder removing solid matter from the surface of said screen and comminuting it by cooperation with said comb in an area spaced upstream from said screen.

5. An apparatus for treating sewage which includes a screen placed in a channel or conduit through which sewage flows, said screen forming a barrier to prevent lumps of solid matter from flowing through said screen and into the sewage stream which flows in that portion of said channel or conduit beyond said screen, a transfer and comminuting unit comprising a cutting cylinder disposed adjacent the upstream surface of the screen, a plurality of teeth projecting laterally from said cutting cylinder, and a comb positioned adjacent said cutting cylinder in an area spaced from said screen, said cutting cylinder being of substantially the same height as the height of said screen, and means for rotating said screen and said cutting cylinder at different

speeds whereby substantially the whole outer surface of said screen is periodically swept by said cutting cylinder, said cutting cylinder removing said lumps of solid matter from the surface of said screen and comminuting them by cooperation with said comb in an area spaced upstream from said screen.

6. An apparatus for treating sewage which includes a screen placed in a channel or conduit through which sewage flows, said screen forming a barrier to prevent lumps of solid matter from flowing through said screen and into the sewage stream which flows in that portion of said channel or conduit beyond said screen, a transfer and comminuting unit comprising a cutting cylinder disposed adjacent the upstream surface of the screen, a plurality of teeth projecting laterally from said cutting cylinder, and a comb positioned adjacent said cutting cylinder in an area spaced from said screen, said cutting cylinder being of substantially the same height as the height of said screen, and means for rotating said screen and said cutting cylinder at different speeds, the screen at a relatively low rate of speed and said cutting cylinder at a relatively high rate of speed, whereby substantially the whole outer surface of said screen is periodically swept by said cutting cylinder, said cutting cylinder removing said lumps of solid matter from the surface of said screen and comminuting them by cooperation with said comb in an area spaced upstream from said screen.

7. In combination with an influent channel and an effluent channel for a moving liquid stream carrying solids to be comminuted, a rotatably mounted drum screen positioned between said channels to prevent unscreened liquid from passing from said influent channel to said effluent channel, a rotatably mounted cutting cylinder positioned in said influent channel adjacent the periphery of said screen, a plurality of teeth projecting laterally from said cylinder and cooperating with said screen for removing solids therefrom, and a comb positioned adjacent said cylinder in a region spaced from said screen, said comb cooperating with said teeth to comminute solids removed from said screen by said teeth in a region spaced upstream from the screen through which the comminuted solids flow, along with the liquid, after they have been comminuted.

8. An apparatus for screening and comminuting solid matter carried in a moving liquid stream, which includes a vertically disposed, rotatably mounted drum screen adapted to be positioned in a channel through which said moving stream flows and form a barrier to prevent the solid matter from flowing through said screen, a vertically disposed, rotatably mounted cutting

cylinder positioned adjacent the periphery of said screen, a plurality of teeth projecting laterally from said cylinder and adapted to cooperate with said screen for removing screened solids therefrom, and a vertically disposed comb positioned adjacent said cylinder in a region spaced from said screen and with the cutting cylinder intermediate said screen and said comb, said comb cooperating with said teeth to comminute solids removed from said screen by said teeth in a region spaced from the screen, and means for rotating said screen and said cutting cylinder at different speeds, the screen at a relatively low rate of speed and the cutting cylinder at a relatively high rate of speed, whereby the teeth on the cutting cylinder transfer screened solids from the screen to the comb and comminute them at the comb.

9. An apparatus for screening and comminuting solid matter carried in a moving liquid stream, which includes a rotatably mounted drum screen adapted to be positioned in a channel through which said moving stream flows and form a barrier to prevent the solid matter from flowing through said screen, a rotatably mounted cutting cylinder positioned adjacent the periphery of said screen, a plurality of teeth projecting laterally from said cylinder and adapted to cooperate with said screen for removing screened solids therefrom, and a comb positioned adjacent said cylinder in a region spaced from said screen and with the cutting cylinder intermediate said screen and said comb, said comb cooperating with said teeth to comminute solids removed from said screen by said teeth in a region spaced from the screen, and means for rotating said screen and said cutting cylinder at different speeds, the screen at a relatively low rate of speed and the cutting cylinder at a relatively high rate of speed, whereby the teeth on the cutting cylinder transfer screened solids from the screen to the comb and comminute them at the comb.
